UNITED STATES PATENT OFFICE.

JOHN KEILS, OF DETROIT, MICHIGAN.

DESIGN FOR AN OIL-STOVE.

SPECIFICATION forming part of Design No. 22,592, dated July 4, 1893.

Application filed June 5, 1893. Serial No. 476,879. Term of patent 3½ years.

To all whom it may concern:

Be it known that I, JOHN KEILS, a citizen of the United States, residing at Detroit, in the county of Wayne and State of Michigan, 5 have invented and produced a new and original Design for an Oil-Stove, of which the following is a specification, reference being had therein to the accompanying drawing.

The drawing shows an oil stove of my design in perspective view which is deemed sufficient to show the leading features thereof. These consist of a base section A substantially of rectangular shape with rounded corners provided with a crowning top B of 15 which the larger portion of its superficial area is exposed and which simulates in general appearance the form of a cover to the base section. On three sides foot rails C are secured to the cover of the base section and 20 conventional ornamentation is applied to the exposed portions of the cover. Rising from the center of the cover of the base section is a barrel shaped combustion chamber D which is provided with large mica windows E opening 25 out to the four sides. This combustion chamber is partly concealed beneath an enlargement F around the upper end of the

combustion chamber and forming a canopy like top supported on the four corners upon the cover of the base section by tubular legs 30 G which stand out from the corners free from the combustion chamber. The legs are connected by arching in a manner to form niche-like recesses upon the four sides under which niches the mica windows appear in the combustion chamber. The corners of the enlargement F are prominently formed and its top is slightly crowning with simple and distinctly formed outlines. From the center of the enlargement F rises a cylindrical top section H 40 leaving a clear margin around its base. This top section is substantially of conventional form with a dome-shaped cover I surmounted by a vase J or other suitable ornament. 45

What I claim as my invention is—

The design for a stove substantially as herein shown and described.

In testimony whereof I affix my signature in presence of two witnesses.

JOHN KEILS.
